UNITED STATES PATENT OFFICE.

CHARLES A. MARIEN, OF ST. LOUIS, MISSOURI.

SECTIONAL RESILIENT TIRE.

1,089,439.

Specification of Letters Patent. Patented Mar. 10, 1914.

Application filed March 9, 1912. Serial No. 682,768.

To all whom it may concern:

Be it known that I, CHARLES A. MARIEN, a citizen of the United States, residing at St. Louis, Missouri, have invented a certain new and useful Sectional Resilient Tire, of which the following is such a full, clear, and exact description as will enable any one skilled in the art to which it appertains to make and use the same, reference being had to the accompanying drawings, forming part of this specification.

My invention relates to a sectional resilient tire and more particularly to one consisting of two sets of resilient blocks which are arranged side by side so that the joints between one set of blocks are out of alinement with those between the other set of blocks.

The object of my invention is to provide means for detachably securing the resilient blocks in position on the periphery of the wheel.

In the accompanying drawings, which illustrate one form of tire made in accordance with my invention, Figure 1 is a side elevation of a portion of the wheel; Fig. 2 is a top plan view; Fig. 3 is a section taken on the line 3—3 of Fig. 2; Fig. 4 is a side view of one of the blocks, partly in section and partly in elevation; Fig. 5 is a perspective view of one of the outer retaining members and Fig. 6 is a perspective view of one of the central retaining members.

Like marks of reference refer to similar parts in the several views of the drawings.

10 represents the spokes of the wheel which carry a felly 11 of any suitable form. This felly 11 is surrounded by a felly band 12 which projects laterally beyond the felly 11 at both sides as best shown in Fig. 3; 13 represents the sectional blocks of rubber or other suitable resilient material. These blocks 13 are arranged in two sets as best shown in Fig. 2, the blocks being staggered, that is the spaces between the blocks of one set are arranged out of alinement with the spaces of the blocks of the other set. Each of the blocks is provided at each side with a projection 14; this projection 14 preferably consists of a hard rubber core 15 which extends below the block and is provided with strengthening bars 16, preferably of metal. The soft rubber of the blocks 13 is extended downward at the end of the blocks 55 to cover the hard rubber as shown at 29.

These end extensions 29 abut firmly against each other when the blocks are in position and thus prevent the separation of the hard and soft rubber which might take place if this extension were not used. While I prefer to form the projections in this manner, I do not desire to limit my invention to such construction as the projections may be formed in any suitable manner, such for example as is shown in my prior Patent, No. 65 979,869, granted to me December 27, 1910.

In order to secure the blocks in position on the periphery of the wheel, I provide a number of outer retaining members 17 shown in detail in Fig. 5, and a number of central retaining members 18, shown in detail in Fig. 6. Each of the outer retaining members 17 is provided with a pair of pockets 19 adapted to receive the projections 14 at the outer sides of the resilient blocks 13.

The retaining members 17 are held in position on the periphery of the wheel by means of bolts 20 passing through openings 21 in the set of blocks 17 and through openings in the projecting edges of the felly band 12. The inner ends of the bolts 20 are engaged by nuts 22. Each of the inner retaining members 18 is provided on one side with a pocket 23 for engaging one of the projections 14, and on the other side with a pair of pockets 24, also for engaging the projections 14. It will be seen that the inner blocks 18 are so shaped that they overlap each other and each member is arranged with its single pocket at the opposite side 90 to the member preceding and the one succeeding it. The members 18 are held in position by bolts 25 passing through openings 26 in the said members and through the felly band and felly. The inner ends of the bolts 25 are engaged by nuts 27.

It will be evident that by means of my construction, a simple and effective method of holding the staggered blocks in position is attained, and, at the same time, any block 100 may be rapidly removed and replaced by a new one by simply unscrewing the nuts 22 and 17 which hold the retaining members in engagement with that particular block. The arrangement is also such that the spaces 105 between the various blocks 13 may be reduced so as to cause no jar as the wheel passes from one block to another. In order to prevent cutting of the block 13 by the retaining members 17 and 18, I prefer to 110

slightly bevel the inner edges of the members 17 and both edges of the members 18, as is shown in Fig. 3 of the drawings.

Having fully described my invention, 5 what I claim as new and desire to secure by Letters Patent of the United States is:

1. The combination with a wheel, of a double row of resilient sectional blocks provided with lateral projections, retaining 10 members arranged at the outer edge of each set of blocks and engaging with the projections, overlapping retaining members arranged between the sets of blocks and also engaging with the projections, said latter 15 retaining members being each provided with pockets on both sides, the pockets on one side being greater in number than those on the other side, and means for securing said retaining members to the periphery of the 20 wheel.

2. The combination with a wheel, of a double row of resilient sectional blocks provided with lateral projections, retaining members arranged at the outer edge of each set of blocks and engaging with the projections, 25 overlapping retaining members arranged between the sets of blocks, and also engaging with the projections, said latter retaining members being each provided on one side with one pocket and on the opposite side 30 with two pockets, and means for securing said retaining members to the periphery of the wheel.

In testimony whereof, I have hereunto set my hand and affixed my seal in the presence 35 of the two subscribing witnesses.

CHAS. A. MARIEN. [L. S.]
